UNITED STATES PATENT OFFICE.

EUGENE PAULUS, OF PHILADELPHIA, PENNSYLVANIA.

IMPROVEMENT IN WATCH-WINDING CLICKS.

Specification forming part of Letters Patent No. **83,788**, dated November 3, 1868.

To all whom it may concern:

Be it known that I, EUGENE PAULUS, of Philadelphia, in the county of Philadelphia, State of Pennsylvania, have invented an Improvement in Watches, of which the following is a full, clear, and exact description, reference being had to the accompanying drawings, making a part of this specification, in which—

Figure 1 represents the frame of a watch-movement termed "three-fourths plate." Fig. 2 represents the top plate removed from its place and reversed. Figs. 3 and 4 represent the click and ratchet-wheel out of their recesses.

The object of this invention is to construct a new style of watch-winding click-work, of which the peculiar arrangement and shape make it stronger than usual, and not liable to break or get out of order, being held in proper recesses made in the thickness or upper part of a top plate well adapted to leave in view the greater part of the work, as seen in Fig. 1.

E denotes the click, made of a round piece of steel, and cut, as the anchor of the lever-escapement, so as to catch properly the teeth of the ratchet-wheel, and adjusted in a solid manner in a recess made in the thickness or upper part, F, managed in the working out of the plate so as to move on its center, and resist, by its full size, the action of the mainspring. It is held, together with the ratchet-wheel, by the delicately-shaped and hardened-steel bridge L.

The top plate, C, is held on the pillars or

front plate by the three screws a b c, and d is a screw to fasten the movement in the case.

In G is seen the double-cap-jeweled bridge for the staff of the pallet and escapement-wheel, and made of gold or hardened steel. In H is the revolving barrel for the mainspring, as usual.

Fig. 2 is an inside view of the reversed plate to show the click-spring M inserted in the thickness of the plate by means of a bevel or snap edge, and acting, in N, on the pin-screw of the click passing through the plate.

Fig. 3 is the click taken out of its recess to show better its shape and thickness and the pin-screw P, which acts on the click-spring M, Fig. 2.

Fig. 4 is the ratchet or click wheel, with its square center hole, to be held on the winding-arbor, as usual.

What I claim is—

1. The improved watch-winding click, made in a round shape, cut so as to catch the teeth of the ratchet-wheel, and adjusted in a recess of the top plate, to resist, by its full size, the power of the mainspring, in the manner substantially as described.

2. The combination of the winding-click E, bridge L, spring M, and pin-screw P, arranged and operating substantially as described.

Philadelphia, May 4, 1868.

E. PAULUS.
